FISHING PLUG

Andrew Horeck, 1872 Kelvin St., Sudbury,
Ontario, Canada

Filed Feb. 26, 1962, Ser. No. 68,987

Term of patent 14 years

(Cl. D31—4)

Fig. 1

Fig. 2

Fig. 3

Fig. 4

Fig. 5

FIGURE 1 is a top plan view of a fishing plug showing my new design;

FIGURE 2 is a side view;

FIGURE 3 is a front end view;

FIGURE 4 is a rear end view;

FIGURE 5 is a bottom plan view.

My design for the fishing plug disclosed is characterized by the exact shape as shown.

I claim:

The ornamental design for a fishing plug, as shown and described.
